CLAIM

The ornamental design for a packing box, as shown and described.

DESCRIPTION

FIG. 1 is a front perspective view of the packing box showing my new design, showing in an open configuration; FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a front perspective view thereof, showing in a closed configuration.

The broken lines shown in the drawings are for the purpose of illustrating parts of the article that form no part of the claimed design.

1 Claim, 9 Drawing Sheets
